(57) **CLAIM**

The ornamental design for an end lug for roller screen frame, as shown and described.

DESCRIPTION

FIG. 1 is a front perspective view of an end lug for roller screen frame, showing my new design;

FIG. 2 is a top plan view thereof;

FIG. 3 is a right side elevational view thereof, the left side being a mirror image;

FIG. 4 is a front end view thereof;

FIG. 5 is a rear end view thereof; and,

FIG. 6 is a bottom plan view thereof.
